APPARATUS FOR THE LIQUID TREATMENT
OF PACKAGES OF YARNHerbert Oswald Naumann, New York, N. Y., as-
signor to Oscar Kohorn & Co., Ltd., New York,
N. Y., a corporation of New York

Application July 26, 1946, Serial No. 686,333

5 Claims. (Cl. 68—198)

1

The present invention relates to an improved apparatus for the liquid treatment of porous packages and it relates more particularly to an improved apparatus for liquid treating and washing tubular cakes of rayon or other thread-like material.

In the manufacture of rayon and other artificial filaments the filament is initially spun and then wound into tubular cakes or packages, the cakes or packages thereafter being subjected to numerous liquid-treating and washing stages. For example, in the manufacture of viscose rayon, these cakes are subjected to the sequential steps of washing, desulphurizing, further washing, bleaching, washing, removing traces of bleaching agent by means of acid treatment, washing, finishing, sizing and dyeing. Thus it is obvious that the aftertreatment of viscose rayon involves a large number of liquid treating steps.

In one of the methods presently employed in the liquid treatment of cakes of artificial filament, the treating liquid or wash water is introduced under pressure into the interior of the cake, the open ends of the cake being suitably sealed. The treating liquid is forced through the walls of the cakes by the pressure exerted by the liquid. Generally, several tubular cakes are stacked end to end, one end of the stack of cakes being sealed and the treating liquid under pressure being forced into the interior of the cakes through the other end. The treating liquid seeps through the cakes thus effecting the liquid treatment thereof. Inasmuch as the individual cakes are subject to swelling or expansion during some of the liquid treatments and to contraction during other of the liquid treatments, it is obvious that if no arrangement is provided, which will allow or compensate for such expansions and contractions there will be a distortion of the cakes and a separation of the cakes permitting the free flow of the liquid between the cakes rather than through them.

It is obvious that any distortion of the cakes might result in the poor and ineffective treatment thereof. Numerous arrangements have heretofore been proposed to permit free expansion and contraction of a stack of cakes but these proposed arrangements have either proved ineffective or too complicated to be put into practical operation.

It is therefore, an object of the present invention to provide an improved apparatus for

2

the liquid treatment of cakes and packages of thread.

Another object of the present invention to provide an improved apparatus for the treatment of tubular cakes of artificial filament.

Still another object of the present invention to provide an improved apparatus for liquid treating and washing tubular cakes of artificial filament whereby allowance is made for the contraction and expansion of the several cakes during the numerous liquid treatments thereof.

A further object of the present invention is to provide an improved apparatus for the liquid treatment of tubular cakes of artificial filament whereby the cakes of artificial filament are subject to a minimum of longitudinal stress.

The present invention broadly contemplates the provision of a seal at the end of a tubular cake the provision of a fluid-tight connection between the confronting faces of a pair of adjacent cakes disposed end to end which seal or connection is responsive to the pressure of the treating liquid to effect the hermetic sealing or fluid tight coupling of the cakes.

25 In accordance with one embodiment of the present invention, the tubular cakes of artificial filament are vertically stacked and the individual cakes are supported by corresponding shelves, the cakes being in liquid communication with each other by way of apertures formed in each of the shelves. The shelves are vertically separated from each other distances greater than the height of the individual cakes and are provided with self-sealing gaskets as will be hereinafter described. These gaskets co-operate with the upper faces of the corresponding cakes and are forced into fluid type relationship with such upper face by means of the treating liquid introduced under pressure into the interior of the cake.

In accordance with another embodiment of the present invention a tubular perforated supporting member has mounted thereon, a series of removable plates between which plates may be positioned tubular cakes of artificial filament. Further, each of these plates is provided on its lower face with a pressure responsive self-sealing gasket whereby upon the introduction of liquid under pressure into the interior of the cakes by way of the perforated tubular member, these gaskets effect a liquid type connection between the vertically adjacent cakes.

It should be noted that inasmuch as the shelves or cake supporting plates are spaced at distances greater than the height of the sup-

ported cakes and inasmuch as the self-sealing gaskets are formed of a resilient material each of the cakes is permitted to expand and contract with great ease without distortion to the cakes or without breaking the hydraulic seal between the respective cakes or between the top cake and the sealing member therefor. It is thus obvious that the present invention provides an improved simple apparatus and method for washing and liquid treating cakes of artificial filaments without unduly stressing or distorting the cakes.

Additional features of the present invention will be apparent from a reading of the specification in connection with the accompanying drawings in which Fig. 1 of the front detailed view of an apparatus embodying the present invention, said view being partially broken away; Fig. 2 is a front elevational view thereof and Fig. 3 is a side elevational view both partially broken away; Fig. 4 is a front elevational view of another form of the apparatus embodying the present invention, said view being partially broken away; Fig. 5 is a transverse sectional view of a self-sealing gasket in accordance with the present invention; Figs. 6-9 are detailed views partially broken away, illustrating the operation of the self-sealing gasket.

Referring now to the drawings and more particularly to Figs. 1-3 thereof, a carriage or truck 11 is provided with flanged wheels 12 whereby the truck 11 and the supported equipment may be easily transported to successive treating stations. The truck 11 suitably supports a pair of oppositely disposed base or bottom plates 13, the bottom plates 13 having formed therein a plurality of regularly arranged apertures 14. Mounted below the bottom plate 13 is the liquid distributing chamber 16. The liquid distributing chambers 16 are suitably secured to the plates 13 by means of bolts 17 and are hermetically sealed to plates 13 by means of suitable gaskets 18. The chamber 16 may be connected to a suitable source of treating fluid by way of the Y-connection 19 which is provided with a flanged end to facilitate its connection to a suitable fluid reservoir or conduit.

The truck 11 also has mounted thereon, a pair of oppositely disposed uprights 20, which uprights are provided with a series of vertically separated and aligned bearings 21. The bearings 21 have rotatably mounted therein a series of spaced shafts 22, each of the shafts 22 rigidly mounting a swingable cake supporting shelf 23. Upper shafts 22 rigidly support a swingable top sealing shelf 24. Further, the shafts 22 have rigidly secured thereto, levers 26, the levers 26 forming an obtuse angle with the shelves 23 and the top member 24. Moreover, the weight of the shelves and the top member 23 and 24 are biased or counterbalanced by means of heavy tension springs 27 having their ends adjustably connected to the depending plates 28 by way of the adjustable eyebolts 29. The other ends of the tension springs 27 are connected by way of pulleys 30 and cables 32 to the free ends of the levers 26. The tension springs 27 and the angle between the lever 26 and the shelves 23 and the top 24 are so adjusted that the shelves will remain in biased open and closed position and require a minimum of effort to shift the shelves from the one to the other position. Suitable housings 33 and 33A enclose the counterbalancing mechanism in order to reduce the corrosive action of the treating fluid on such mechanism.

Considering now the cake supporting shelves 23 and the top member 24, each of the shelves are provided with a series of apertures 34 which are in vertical alignment with apertures 14 formed in the bottom plate 13 when the shelves are in closed position. Further, each of the shelves 23 and the top member 24 are provided with fluid pressure responsive self-sealing gaskets 36, the gaskets being of annular shape as will be hereinafter described. The gaskets 36 are positioned on each of the shelves 23 and on the top member 24 in coaxial arrangement with respect to the apertures 34 and 14. Moreover, the gaskets 36 are mounted on the shelves 23 and on the top member 24 by means of a collar 37 provided with an inwardly extended flange which flange is engaged by suitable securing means such as rivets 38. In addition to supporting the gaskets 36, the rivets 38 secure suitable locating rings 39 to the upper faces of the shelves 23. Locating rings 39 are also positioned on the bottom plate 13.

The bottom plate 13 and the shelves 23 are provided with upstanding borders 40 along three edges thereof and with depending lips 41 along their inner edges. The shelves 23 and the top member 24 are also provided with depending spacer bars 42 positioned at the outer end of the shelves 23 and the top members 24. The spacer bars 42 are of such length that in co-operation with the shafts 22 they support the shelves 23 and the top members 24 in horizontally parallel position. Further, locking rods 43 pivotally connected to the bottom wall 13 terminate in C-shaped clamps 44 which C-shaped clamps are provided with wing bolts 46. Bars 46A extending from the top members 24 co-operate with the clamps 44 whereby the entire apparatus may be locked into operative position.

A trough 47 is positioned between the vertical stacks of shelves 23 and lies in the path of the lips 41. Thus the treating liquid which is forced through the treated cakes is allowed to flow into this trough and is from there conducted either to a waste conduit or to any other desired treating apparatus. Further, liquid baffle members 48 are suitably mounted in the chambers 16 directly in the paths of the liquid inlets to the chambers 16 in order to evenly distribute pressure of the treating liquid.

Considering now the operation and manipulation of the apparatus illustrated in Figs. 1-3, the top member 24 and the shelves 23 are swung into open and substantially vertical position. Porous cakes 49 of rayon or any other material which is to be treated are positioned on the bottom plate 13 within the locating rings 39 and the next upper shelf 23 swung to closed horizontal position. This operation is repeated until all the shelves 23 are loaded with the cakes 49 and the upper member 24 is then swung into closed horizontal position and the entire apparatus is locked by means of the C clamps 44 and the bars 46A. The carriage or truck 11 is then transported to a fluid treatment station and the bottom flange of the Y-connector 19 is suitably connected to a conduit which in turn is connected to a treating liquid under pressure. Liquid under pressure is allowed to flow through the Y-connection 19 and the distributing chambers 16 into the interior of the cakes 49. The treating liquid effects a fluid type sealing between the upper ends of the cakes and the lower faces of the gaskets 36 as will be hereinafter described in greater detail. The treating liquid is forced through the porous cakes

49 effecting the treatment thereof, the liquid thereafter flowing along the shelves 23 and the bottom plate 13 exterior to the cakes 49 to the depending lips 41 and into the return trough 47. After the cakes have been treated with the treating liquid for the desirable length of time, the treating liquid is turned off and the excess liquid allowed to flow from the apparatus. The Y-connection 19 is then disconnected from the treating liquid conduit. This operation is continued until the complete aftertreatment of the cakes is completed.

In Fig. 4 of the drawings there is illustrated another form of equipment embodying the present invention wherein the cakes 49 are supported on tubular conduits which conduct the treating fluid to the supported cakes. More particularly, a stepped conduit 50 which has the apertures 51 formed in the wall thereof is supported on the bottom plate 13 by means of a coupling member 52. The coupling member 52 provides a fluid communication between the interior of the perforated conduit 50 and the fluid distributing chamber 16.

The conduit 50 is formed of a series of perforated tubular members 53, the tubular members 53 being of successively smaller diameter. The upper ends of the tubular members 53 are provided with inwardly extending flanges 54 which flanges overlay sleeve members 55. The sleeve members 55 are suitably and rigidly fixed to the corresponding inner walls of the tubular members 53. Moreover, the sleeve members 54 are also rigidly secured to the lower outer walls of the following upper tubular members 53 thereby providing the single rigid stepped tubular conduit 50. The upper end of the topmost tubular member 53 is capped with the member 56 which forms the male portion of a bayonet joint.

There is supported on each of the ledges formed by the flanges 54 a removable cake supporting shelf 57, the shelves 57 being of circular horizontal cross-section and having circular apertures 58 formed therein of successively smaller diameter, the edges of the apertures 58 being provided with upstanding flanges 59. Further, the shelves 57 have channel shape peripheries 60 which engage the outer portions of the self-sealing gaskets 36. In order to securely lock the gaskets 36 in position there are provided locking rings 61 of angular cross-section which rings 61 co-operate with the channel shape peripheries 60 to suitably support the gaskets 36. The coupling member 52 is provided with an outwardly extending ledge 63, the ledge 63 suitably supporting by means of fasteners 64, a disc shaped shelf 65. A top member 66 of substantially the same shape as the shelves 57, similarly supports a gasket 36. The top member 66 is provided with the hollow cap portion 67, having inwardly projecting lugs 68 to form the female portion 56. The shelf 66 is rigidly fixed to the cap portion 67.

Considering now the operation of the equipment illustrated in Fig. 4, the upper member 66 and the shelves 57 are removed from the supporting conduit 50. A cake is positioned on the lower shelf 65 coaxial with the conduit 50 and a shelf 57 is superimposed on the cake 49, the shelf 57 having an aperture of slightly smaller diameter than the outer diameter of the corresponding ledge 54 which supports the shelf 57. Cakes 49 and shelves 57 are successively positioned on the conduit 50 until the conduit is fully loaded and the top sealing plant 66 is then placed

on the end of the conduit and suitably locked in position by means of the bayonet joint including the members 66 and 67. The cakes are then treated in the manner described in connection with the first embodiment of the present invention.

Referring now to Figs. 5-9 of the drawing, the fluid pressure responsive self-sealing gasket 36 is preferably formed of rubber or other suitably resilient material. The gasket 36 is formed of an annular supporting portion 70 having an inwardly and downwardly extending connecting portion 71. Projecting inwardly from the connecting portion 71 is a relatively flexible flange portion 72 which forms a small angle with the horizontal. The flange portion 72 terminates in a tapered edge 73. Projecting upwardly from the flange portion 72 and extending from the tapered edge thereof to the connecting portion 71 are the radially disposed ribs 74 regularly arranged along the flange 72.

When the cakes 49 and the gasket supporting shelves are locked in position and prior to the introduction of a treating fluid the gasket should preferably assume a shape as illustrated in Fig. 9 of the drawings. Upon introduction of a treating fluid under pressure into the interior of the cakes such fluid will enter the space between the upper face of the flange 72 of the gasket 36 and the confronting lower face of the supporting shelf. Inasmuch as there is a pressure gradient through the porous cakes 49, the pressures on the bottom faces of the flanges 72 are less than the pressures in the corresponding upper faces of these flanges thus resulting in the flanges 72 being urged into fluid tight contact with the confronting upper faces of the cakes 49. It is apparent that any changes in the longitudinal dimensions of the cakes 49 are taken up by the gaskets 36 with very little stress on the cakes 49. Thus in Fig. 7 there is illustrated a cake 49 in greatly expanded position. It should be here noted that the radial flanges 74 are provided in order to prevent the upper faces of the flanges 72 from coming into contact with the lower faces of the supporting shelves so that the treating fluid at all times has access to the space between flange 72 and the supporting shelf. Thus the flanges 72 will not be locked into upper position where they might not follow the subsequently contracting cake.

Prior to the introduction of the treating fluid, the gaskets 36 may assume the position shown in Fig. 8 of the drawings or may assume the position where the flanges do not come in contact with the confronting end face of the cake 49. It has been found that upon the introduction of the treating fluid under pressure, even when the flanges 72 assume the latter position, a fluid tight seal is immediately effected between the cakes 49 and gaskets 36.

The method and apparatus herein described are the best embodiments of the present invention now known, but it is to be understood that the invention is not necessarily or specifically limited thereto, in all cases, but, under suitable conditions may be carried out in other ways without departure from its spirit and within the proper scope of the following claims.

I claim:

1. An apparatus for the liquid treatment of unmounted tubular packages of yarn comprising a plurality of package supporting platforms having apertures formed therein, means independent of said packages of yarn for horizon-

tally supporting said platforms in vertically spaced positions, whereby said apertures are in substantial alignment and flexible annular gaskets secured along their outer peripheries to the lower faces of said platforms, and being substantially coaxially arranged with respect to said apertures, the inner edges of said gaskets being spaced from the lower faces of said platforms.

2. An apparatus for the liquid treatment of tubular packages of yarn comprising a plurality of vertically spaced hinged platforms having apertures formed therein, which apertures are in substantial vertical alignment when said platforms are in horizontal position, and flexible annular gaskets arranged coaxially with respect to said apertures, and having their outer peripheries supported in fluid tight relationship with said platforms and their inner peripheries spaced from the planes of their respective supporting platforms.

3. An apparatus for the liquid treatment of tubular packages of yarn comprising a plurality of vertically spaced hinged platforms having apertures formed therein, which apertures are in substantial vertical alignment when said platforms are in horizontal position, and flexible annular gaskets of concavo-convex shape arranged coaxially with respect to said apertures and having their outer peripheries supported in fluid type relationship with said platforms and their inner peripheries spaced from the planes of their respective supporting platforms.

4. An apparatus for the liquid treatment of tubular packages of yarn comprising a plurality of vertically spaced hinged platforms having apertures formed therein, which apertures are in substantial vertical alignment when said platforms are in horizontal position, and flexible annular gaskets of concavo convex shape having upstanding radial ribs formed on the concave

5 face thereof, arranged coaxially with respect to said apertures and having their outer peripheries supported in fluid type relationship with said platforms and their inner peripheries spaced from the planes of their respective supporting platforms.

10 5. An apparatus for the liquid treatment of unmounted tubular packages of yarn comprising a plurality of package supporting platforms having apertures formed therein, means independent of said packages of yarn for horizontally supporting said platforms in vertically spaced positions, whereby said apertures are in substantial alignment and flexible annular gaskets of concavo-convex shape secured along their outer peripheries to the lower faces of said platforms, and being substantially coaxially arranged with respect to said apertures, the inner edges of said gaskets being spaced from the lower faces of said platforms.
